SANDING MACHINE

Bryan D. Pinkney, Smithville, N. J., assignor to
 H. B. Smith Machine Company, Smithville,
 N. J., a corporation of New Jersey

Application February 28, 1930. Serial No. 432,001

2 Claims. (Cl. 51—34)

This invention relates to a sanding machine and has particular reference to mechanism for axially oscillating drums of machines of this character.

5 In order to prevent the formation of grooves in the surface of wood being sanded, it is customary to oscillate one or more of the sanding drums of such machine axially whereby the surface is more evenly smoothed and markings which would ordinarily result from axially stationary drums are eliminated. It has been common heretofore to impart such axial oscillation to drums by means of levers which are rocked by eccentrics mounted on a drive shaft. Devices of this character have generally a relatively large number of connections where play may occur causing noise in operation of the machine. Furthermore such devices must be carefully made and are relatively expensive.

10 It is accordingly the broad object of the present invention to provide an oscillating means which not only imparts smooth movements to the drums, but is also simple in construction and has few parts, whereby wear is considerably reduced.

15 Detailed objects of the invention relating to the provision of means for automatically maintaining the oscillating mechanism in operative relationship with the drum when the same is tilted, and other details of construction will be apparent from the following description read in conjunction with the accompanying drawings, in which:

20 Fig. 1 is a side elevation of the machine embodying the present invention;

25 Fig. 2 is a fragmentary sectional view showing details of the construction;

30 Fig. 3 is a sectional view showing the connection of the eccentric pin to an oscillating block whereby oscillating motions are imparted to a drum; and

35 Fig. 4 is a plan view of the subject of Fig. 3.

The machine, which is of a standard type of construction, comprises a frame 2 in which is mounted a feed belt 4, indicated in dotted lines, for carrying work beneath successive sanding drums 6, 8 and 10. As is customary in machines of this character, the first sanding drum has no oscillation imparted to it whereas the second and third sanding drums 8 and 10 have axial oscillations imparted thereto. While only three drums are shown, it will be obvious that more or less may be provided and that the invention is applicable to one or more drums of this general character. The sanding drums are either belt

driven or motor driven. In the latter case separate motors are provided to drive the drums. A braking device 12, of the character disclosed in my prior Patent No. 1,715,385, dated June 4, 1929, is provided to stop the drums quickly when desired.

40 The drums are mounted in suitable bearings indicated generally by the numeral 20 carried in vertically adjustable brackets 14, 16 and 18, these brackets being duplicated on the opposite side of the machine. Separate adjustments of these various brackets serve to tilt independently the axes of the drums as may be desired.

45 Referring to Fig. 2, wherein the details of one of these bearings is disclosed, namely, the one associated with the axial oscillating sanding drum 8, 22 indicates an outer housing which is carried upon the bracket 16. An axially perforated pin 24 is threaded into the top of this housing and is arranged to conduct lubricant into the housing from a pressure device which may be secured in the usual fashion to the valve nipple 26. The pin 24 projects loosely within an opening in an annular ring 28 in which are clamped the outer races 30 of two roller bearings, the

50 races being held in suitably spaced position by a ring 32 and being clamped by facing rings carried on the opposite sides of the ring 28. The inner faces of the races 30 are smooth so that the rollers 34, which are maintained in grooves in the inner races of the bearings, may slide axially therein. Accordingly, even though the bearing 20 is stationary during operation, the

55 shaft carrying the sanding drum 8 may oscillate in an axial direction. To permit free tilting of the axis of the sanding drum relative to the bearing, the ring 28 and the housing are provided with bearing surfaces, as indicated at 36, preferably curved about the pin 24 as center, so that

60 relative movement can take place at these surfaces without producing any binding of the moving parts. The construction of bearing disclosed is more fully described and claimed in my co-pending application Ser. No. 432,002, filed February 28, 1930.

65 The inner race 38 of a ball bearing is secured to the outer end of the shaft of the sanding drum 8. The balls of this ball bearing are maintained in grooves in the inner race 38 and the outer race 40, so that relative axial movements of the two races cannot take place. Accordingly any movements imparted to the outer race in an axial direction will be transmitted to oscillate the sanding drum.

70 The outer race 40 is clamped between a cas-

ing 42 and its cover 44. These two members are formed to provide a slideway extending transversely to the direction of the axis of rotation and in which slides a block 48 having a vertical bore 50 therein receiving a pin 52 carried eccentrically to its axis by a shaft 54. A spring 56, reacting between the block 48 and a bearing 58 carried by the frame, tends to maintain the block in its uppermost position against the top of the groove in the casing, whereby rattling is prevented which would normally occur if the end of the drum in question were lifted relatively to the frame. It will also be noted that this maintenance of the block 48 against the top of the groove prevents the housing 42 from turning about the axis of the drum. The block 48 is, of course, free to slide upwardly on pin 52.

The two shafts 54 which are provided in the present instance carry bevel gears 60 at their lower ends, meshing with bevel gears 62 on a shaft 64 driven by the usual reduction gearing. It may be noted that the shaft 64 corresponds to the shaft usually provided in such machines to carry the eccentrics which serve to oscillate the levers, which in turn impart oscillating movements to the drums. By reason of the provisions of set screws or similar detachable connections between the bevel gears 62 and the shaft 64, the bevel gears may be readily freed from the shaft and moved axially therewith to take one or both out of mesh with their corresponding bevel gears 60, so that, if desired, the sanding drum or drums may be operated without axial oscillation.

Lubricant for the ball bearing within the housing 42 is provided through a nipple 68. It will be noted that this housing, as well as the housing of the bearing 20, form lubricant chambers and are provided where the shaft passes therethrough with grease collecting rings so that a

constant supply of lubricant is maintained at the various bearings.

The connections just described impart very smooth oscillating movements to the drums with a minimum of wear and without noise. This is primarily due to the minimum number of connections and the fact that rotating parts are used whereby inertia of movement which might impart jars to the machine is prevented.

What I claim and desire to protect by Letters Patent is:

1. A sanding machine including a frame, a sanding drum, an axially oscillatable shaft mounting the drum in the frame, a member carried by the shaft and secured against endwise movement relatively thereto and providing a slideway extending transversely to the shaft, a block arranged to slide in the slideway, a shaft extending approximately at right angles to the first mentioned shaft, an eccentric member carried by the second shaft and engaging the block, an adjustable bearing for the first shaft, and resilient means for holding the block in proper position in the slideway in various positions of adjustment of the shaft. 90

2. A sanding machine including a frame, a sanding member including an axially oscillatable shaft, a member carried by the shaft and secured against endwise movement relatively thereto and providing a slideway extending transversely to the shaft, a block arranged to slide in the slideway, a shaft extending approximately at right angles to the first mentioned shaft, an eccentric member carried by the second shaft and engaging the block, an adjustable bearing for the first shaft, and resilient means for holding the block in proper position in the slideway in various positions of adjustment of the shaft. 105
